UNITED STATES PATENT OFFICE.

GEORGE BERTHOLD SAMUELSON, OF ISLEWORTH, AND WILLIAM HENRY GLASER, OF TUNBRIDGE WELLS, ENGLAND.

RAILWAY SYSTEM.

1,353,423.

Specification of Letters Patent. Patented Sept. 21, 1920.

Application filed May 12, 1920. Serial No. 380,949.

To all whom it may concern:

Be it known that we, GEORGE BERTHOLD SAMUELSON and WILLIAM HENRY GLASER, subjects of the King of England, residing, respectively, at Isleworth, in the county of Middlesex, England, and Tunbridge Wells, in the county of Kent, England, have invented certain new and useful Improvements in Railway Systems of which the following is a specification.

This invention is for improvements in or relating to railway systems and has for its object to provide a railway or the like serving a large number of stations, wherein a high average speed is maintained, or in other words, the time occupied in traveling between any two given stations is reduced to a minimum.

This invention therefore comprises a railway system wherein the aggregation of vehicles constituting a train does not stop at each station, but a coach is slipped from the train to provide transport to the station and another coach to provide transport from the station is started therefrom in advance of the train so as to be overtaken by it and coupled to it; means are provided to establish communication between the individual coaches when coupled together in a train.

Passengers boarding a coach at a station remain in that coach until it is coupled up to the train which has overtaken it and then walk toward the rear of the train until they reach a coach allotted to the station at which they wish to alight. They remain in this coach until it is slipped from the train and stops at that particular station. It will be seen therefore that as far as any individual passenger is concerned the train in which he is traveling does not stop from the time he enters the coach at the station until he leaves another coach at his destination.

It will further be seen that the train slips a coach at each station to be served and picks up another coach from that station so that each coach in turn, after standing at a station, becomes the front coach of a train and then progresses rearwardly through the train until it becomes the last coach, when it is slipped and stops at another station. In the case of a "circular" railway, it might be arranged that a coach stops only at one station, making one complete circuit of the line each time it starts.

Preferably the railway track is arranged

in the form of a closed ring around which the trains circulate without stopping. Obviously however the invention can be applied to an ordinary railway in which the train is arranged to stop only at the terminus at each end.

Further it will be appreciated that the number of coaches allocated to a station will depend upon the number of passengers desiring to travel to or from that station, and that such group of carriages will be picked up by the train and slipped by the train as a unit. For simplicity in the description hereafter however, it will be assumed that only one coach is slipped at each station.

The invention is most advantageously applied to a railway system in which the vehicles are electrically propelled and it will be described as applied to such a system.

When a coach leaves a station in advance of a train it is gradually accelerated up to a speed approximately equal to that of the train but preferably slightly below it so that the train can overtake it, the shock due to the slight difference in speed being taken by suitable shock-absorbers or buffers.

According to another feature of the invention as applied to an electric railway system, wherein a uniformly moving train overtakes and is coupled to an accelerating coach starting in front of it on the same line, there is provided means for preventing the train from overtaking the coach too rapidly (*i. e.* before the latter has attained the desired speed at which it may be coupled to the train) comprising a control line (for example a line supplying power to the train) for the train divided into insulated sections, and a series of switches to be automatically operated by the passage of the coach which is in advance of the train to energize said sections, said switches being spaced from the starting point of the coach at such intervals predetermined from the acceleration characteristic of the coach, that the coach shall have attained a predetermined velocity and position before it energizes each section of the train-control line, whereby the space interval between the train and the coach is governed by progress or the velocity of the coach.

According to another feature of the invention, similar means may be provided for preventing a coach from attaining such a speed that it cannot be overtaken by the

- train, such means comprising a sectionalized control line for the coach controlled by switches which are operated by the train, the lengths of the sections of control line 5 for the coach and the spacing of the switches operated by the train being such that the power supplied to the coach is cut off unless the train is within the predetermined distance from the coach at any given time.
- 10 According to another feature of the invention each of the said switches controlling a section of a train-control or coach-control line is made in the form of a two-way switch, and is put in series with another 15 two-way switch which is situated at that end of the section at which the train or coach leaves the section. The second switch is adapted to be operated by the vehicle leaving the section, and the whole arrangement 20 is such that a section is energized by the coach (or by the train) to permit the passage therethrough of the train (or of the coach) and when the train or coach has passed through the section it operates the second 25 two-way switch, to deenergize that section.

After the coach has attained its normal full speed and is coupled to the train, it is not necessary for it to draw its power from the coach-control line, as it can draw it instead from the train-line and the coach control-line can therefore be omitted, or a dummy line used between the stations.

In order that the operation of the railway hereinbefore described may be automatic, the 35 coaches, according to another feature of the invention are fitted with means for operating the above-mentioned switches, which means are controlled by the position of the buffers of the coaches to be operative or inoperative according as the front and rear 40 buffers of the coach are either, neither or both engaged with the buffers of another coach. In this way, the single coach which starts from the station and accelerates can 45 be made to operate the energizing switches on the train-control line, but not to operate the deenergizing switches for the sections of that line and similarly the coaches when coupled together in a train will operate only 50 the switches controlling the progress of the coach and the deenergizing switches for its own sections.

According to yet another feature of the invention, in order to insure automatic 55 working, it is necessary that a coach should draw its power from the coach-control line while it is running independently as a coach but that, when coupled to a train, it should draw its power from the train-control line. 60 According to this feature of the invention, therefore, there is provided on each coach a selector-switch device which is operated from the buffers, according as they are engaged with the buffers of other coaches, 65 (i. e. when coupled to a train) or free (when

the coach is independent) to connect the control-circuit or the power-circuit for the motor on the coach to a collecting slipper for the train-control line or coach-control line respectively.

70

The arrangements above described comprising sectionalized control lines and switches for the sections operated by the train and coach respectively, might be sufficient to secure the correct working of the 75 system, but in order to secure still closer regulation of the rate of acceleration, uniform speed and retardation of a coach throughout its cycle of operations, there is preferably provided on each coach a regulating device 80 of the type described in the concurrent British patent application No. 11979 of 1919 in the name of W. H. Glaser. This device comprises a movable mass such as a flywheel, means for imparting to it a uniform velocity 85 or acceleration or retardation, and a differential gear wherof one element is driven by this flywheel and the other element is driven by the coach, (say by one of the running wheels of the coach). The differential device is connected to a suitable controlling device such as a rheostat in the power-circuit of the coach so that the supply of power to the coach is varied to maintain its speed or acceleration or retardation proportional to 90 the predetermined speed or acceleration or retardation at which the flywheel is caused to run.

90

In addition to controlling the supply of power to the coach, this device may also be 100 caused to control electrical braking means on the coach.

95

According to another feature of the invention, turnstiles are provided at the stations to regulate the admission of passengers to 105 the coach standing at the station, and preferably these turnstiles are automatically locked and unlocked according to the position of the approaching train.

100

Other features of the invention will be 110 hereinafter described, and the novel features thereof are pointed out in the claims appended to this specification.

110

In the accompanying drawings which 115 illustrate a particular application of this invention,

115

Figure 1 is a diagrammatic representation of the lay-out of the power and control lines for an electrically operated railway in the neighborhood of a station;

120

Fig. 2 is a partial side elevation of a coach;

125

Fig. 3 is a partial end view looking from the left hand end of Fig. 2 of the same coach;

Fig. 4 is a plan of the connections between the buffers and the controlling switches;

Fig. 5 is a plan of a selector-switch mechanism;

130

Figs. 6, 7, 8 and 9 are diagrammatic views

showing the operation of the switches in Fig. 5;

Figs. 10, 11 and 12 show a preferred construction of switch;

5 Figs. 13, 14 and 15 show diagrammatically the wiring on the coaches, Fig. 13 showing an isolated coach standing at a station, Fig. 14 a train of three coaches, the front coach being at the right hand side, and Fig. 15 an 10 isolated coach after it has been slipped from a train and is approaching a station whereat it is to stop.

Like reference characters indicate like parts throughout the figures.

15 The general construction and arrangement of the railway will first be described with reference to the diagrammatic arrangement shown in Fig. 1, and the details will be described later with reference to the other 20 figures of the drawings.

Referring first to Fig. 1, a single-track railway is indicated at 10 and a station thereon at 11. A power-supply line 12 extends throughout the length of the line 10, 25 but is interrupted and sectionalized between two points 13 and 14 on either side of a station. The train is supposed to travel in this view from left to right as indicated by the arrow 15. At the gap 14 in the power-line 12, which gap is on that side of the station by which the train leaves, two branches 16, 17 are provided. The branch 16 extends as far as the more remote end of the platform at which the coach stops, while the branch 30 17 extends as far as the other gap 13 in the power line 12.

The power-line 12 between the gaps 13 and 14 is divided into a series of insulated sections 18, which for simplicity are illustrated as being of equal length; each section 40 is provided with a two-way switch at that end of the section by which the train leaves, these switches being indicated at A¹, B¹, C¹, D¹, E¹, F¹.

45 The branch-line 16 has arranged along it a number of two-way switches, A, B, C, D, E, F which are connected to the corresponding switches A¹ to F¹ so that power can be supplied from the line 12 through the branch 50 16 and through any pair of switches A, A¹ or B, B¹ and so on, to the corresponding insulated section 18. The switches A to F are spaced apart by such an amount that a coach starting from the station and moving 55 with a predetermined acceleration passes each switch at an interval of time equal to that taken by a uniformly moving train to traverse the length of an insulated section 18. The acceleration and spacing are so 60 chosen that if a coach starts from the switch A at the time a train enters the first insulated section 18, the coach will have attained approximately the same speed as the train when it reaches the gap 14 in the power line,

and the train will have overtaken it about at 65 this time.

The branch line 17 is provided with a series of two-way switches marked respectively a¹, b¹, c¹, d¹, e¹, f¹, spaced along it at intervals, which for convenience are shown 70 as equal to one another. These switches are connected to a series of similar two-way switches, a, b, c, d, e, f which are spaced along the line 19 at intervals such that a coach starting and accelerating from the 75 station passes the switches in successive intervals of time equal to the time in which a uniformly moving train passes the switches a¹ to f¹. The switch a¹ is placed opposite the gap 13 in the power-line 12, and the switch f¹ 80 is placed opposite the gap 14 in the power-line 12. The line 19 terminates at the switch f although it may, if desired, be continued as a completely insulated and inoperative line. The left-hand end of the line 19, is 85 connected at 20 to the power line 12, in order that a coach intended to stop at the station 11 has a power-supply available for use if required until it reaches the station.

Each coach which is used on this railway 90 carries at its forward end a slipper 30, adapted to engage the power supply line 12 or the insulated sections 18 thereof. Each coach further carries at or near its forward end a striker 31, which is adapted to operate 95 the switches A¹ to F¹ as it passes them. Assuming, therefore, that the switches A, A¹ are correctly positioned to supply power to the section 18, the slipper 30 will collect such power but when the coach leaves that 100 section the striker 31 will operate the switch A¹ to cut off the power supply to that section, and this action is repeated with each of the sections.

Each coach also carries at its rear end a 105 slipper 32 and a striker 33 which operate in exactly the same manner to enable power to be collected from the insulated sections of the line 19 and to operate the switches a to f to disconnect the power-supply from each 110 section as the coach leaves that section.

Each coach further carries at its front end a striker 34 to operate the switches a¹ to f¹ and at its rear end a striker 35 to operate the switches A to F. All these strikers and 115 slippers are arranged to be selectively operative in the manner hereinafter described.

The operation of this railway will now be described with reference to a train and individual coaches. Assuming that a coach 40 is standing at the station 11, it occupies a position such that its rear end lies between the switches A and B so that the striker 35 has operated the switch A just before the 120 coach stopped in the station. This operation of the switch A has energized through the switch A¹ the first insulated section 18. The switches a, a¹ are so set that no power 125

is supplied to the short section of the line 19 controlled by them.

Assume next a train made up of five coaches marked respectively 41 to 45 approaching the station 11 from the left. When the front of the coach 41 reaches the gap 13 in the line 12, the striker 34 on that coach operates the switch a^1 and thereby energizes the section of the line 19 with which 10 the slipper 33 of the coach 40 is in contact. The coach 40 therefore starts to move.

The last coach 45 of the train is slipped conveniently at about this time, so that by uniformly retarding its speed it can pull up 15 at the desired point in the station 11.

Since the first insulated section 18 had been made alive by the operation of the switch A, as above-mentioned, the train continues to travel forward, but about the time 20 that it reaches the switch A ^{1} the coach 40 in its progress from the station operates the switch B so as to supply power through the switch B ^{1} to the next insulated section 18 for the train. When the train leaves the 25 first section it throws the switch A ^{1} into the "off" position by means of the striker 31, thereby rendering the first section dead.

At about the same time, the striker 34 on the front coach 41 of the train operates the switch b^1 to supply power to the next insulated section of the line 19 so that the coach 40 is also permitted to continue in movement. When the coach 40 leaves its 30 first insulated section 19 the striker 33 operates the switch a to render the first section 19 dead. This series of switch-operations continues until the coach and the train have both passed the gap 14 at which point the train has overtaken the coach, and the coach 35 has attained a speed equal to or slightly less than that of the train and the two have been coupled together. After the train 41-44 has passed through the station, the coach 45 pulls up in the station, and just before stopping, it operates the switch A so as to render the first section 18 alive. The coach 45 stops before it reaches the switch B, and therefore all the connections are exactly the 40 same as when the coach 40 was standing in the station, and the passage of the next train repeats the whole cycle of operations.

It will be seen, therefore, that when the coach 40 was standing in the station, all the insulated sections 18, except the first one, of the train line 12 were dead, and that all the insulated sections of the line 19 were similarly dead so that no movement of the coach was possible until a train came within a predetermined distance of it and operated the switch a^1 .

Further it will be seen that the progress of the complete train from one insulated section 18 to another is determined by the progress of the coach 40 in advance of it, 65 since if the train for any reason overtakes

the coach too rapidly, it will reach an insulated section 18 before the coach has traveled sufficiently far to operate the switch to energize that section. Similarly, if the coach accelerates too rapidly so that the train cannot overtake it, it also will run into a section 19 which is not energized owing to the train not having reached and operated the appropriate switch for that section. Therefore the coach and the train mutually control 70 each other's position on the track 10 in such a manner that they both arrive at the point 14 at the same time and with the same or approximately the same velocity so that they can be coupled together. The coach 40 then 75 becomes the front coach of the train, which again consists of 5 coaches, 40 to 44 respectively, the rear coach 45 being then stopped in or approaching the station 11.

It will be appreciated that every coach 80 has to be provided with slippers 30, 32 and strikers 31, 34, 33, 35 and that it is necessary that these should be selectively operative as above mentioned, that is to say, when the coach is not coupled up and forming 85 part of the train, only the strikers 33 and 35 are to be operative, the strikers 31 and 34 being inoperative. Similarly, when the coach is coupled to the train the strikers 31 and 34 on the front coach are to be operative, but on the remainder of the coaches all 90 the strikers are to be inoperative, until the coach is slipped from the rear of the train when only the strikers 33 and 35 are to become 95 operative. It is desirable also that 100 the collecting slippers 30, 32 should be selectively operative in the same way. This selective operation of the strikers and switches is affected by operatively connecting them, for example mechanically and 105 electrically, with the front and rear buffers of the coaches so that as these buffers are pressed in or out, so the appropriate connections are made in the manner now to be described.

Referring now to Figs. 2, 3 and 4, each coach-frame 50 is supported on two bogies 51, 52, the bogie 51 being situated at the front end of the coach in its direction of travel. The buffers at the front and rear 115 ends are indicated at 53, 54 respectively and they are connected to any suitable resilient controlling device such as springs and dash-pots mounted in casings 55, see Fig. 4. The selector-mechanism for the switch-gear is 120 mounted in a casing 56 hung on the under side of the frame 50. From this casing 56 there project longitudinally of the frame two plungers 57 and 61 respectively, see Fig. 4. The plunger 57 is connected to a bell-crank lever 58, which lever carries at its 125 other end a roller 59, bearing on a wedge-shaped or conical ended member 60, carried by or movable with the buffers 54. When these buffers are pushed in against the 130

springs 55, the roller 59 rides up the inclined surface 60 at the beginning of such inward movement, and thereby pushes the plunger 57 inward into the casing, or toward the right in Fig. 4. The remainder of the stroke of the buffers does not affect the plunger 57.

The second plunger 61 is connected to the front buffers 53 through a lost-motion device 62, in such manner that the inward movement of the buffers 53 against their springs 55 has no effect on the plunger 61 until they approach the inner limit of their travel.

The rods 63 connecting the buffers with the plunger 61 are bifurcated at 64 and 65 to pass the bogie pin 66 of the front bogie and another piece of apparatus 67 respectively. The connection between the plunger 57 and the bell-crank lever 58 owing to its being slightly eccentric clears the corresponding bogie-pin 68 at the other end of the coach.

The selector-switches in the casing 56 are illustrated in Fig. 5. The arrow Z at the top of the figure indicates the direction of movement of the coach so that the right-hand side of this figure is the forward end and the plunger 61 is connected to the front buffers of the coach as above-described and the plunger 57 is connected to the rear buffers of the coach.

These two plungers 57 and 61 control two main switch members by the movements imparted to them from the buffers. For convenience in description, the position of the plungers will be described as "in" or "out" according to whether they have moved into the casing or out from the casing. That is to say, the plunger 57 is shown in its "out" position, but can be moved "in" toward the right in Fig. 5, and the plunger 61 is shown in its "in" position and is movable to its "out" position also toward the right in Fig. 5.

One of the main switch-members aforesaid 62 is pivoted at 63 and carries at each end an insulated bridging contact 64, 65 respectively. The contact 64 always engages the stud 66 at one end but is movable between two studs 67, 68 at the other end. Similarly the contact-piece 65 always engages a stud 69 at one end but engages one or the other of a pair of studs 70, 71 at its other end. The two contact-pieces are insulated from one another.

The second main switch member 72 is pivoted at 73 and similarly carries bridging contacts 74, 75 which engage respectively contacts 76, 77, 78 and 79, 80, 81 in exactly the same manner as the first-mentioned switch. Each of these main switches has coupled to it an auxiliary switch 82, 83 respectively, these switches carrying insulated bridging contacts by which connection may be made in one case between contact studs

84, 85 and in the other case between contact 65 studs 86, 87.

The two switches 62, 72 are controlled by pins 86 upstanding on them and engaging slots in bars connected to the two plungers 57, 61. The pins 86 and their cooperating slots are so positioned that when the front plunger 61 is "in" it pushes both switches into their "off" positions as shown in Fig. 5. It will be seen that this is effected by arranging one pivot 63 on one side of the plunger 61 and the other pivot 73 on the other side of that plunger. Similarly the rear plunger 57 when pushed in, pushes the switch 72 into its "off" position, but it has a lost motion engagement with the switch 80 62 and does not directly operate it.

A tension spring 88 is provided near the lower ends of the two switch-members 62, 72, tending to draw those ends together and thereby operate the switches when 85 permitted by their engagement with the plungers.

It will be seen on reference to Fig. 5 that the contact 67 is of a greater angular length, measured by the movement of the switch-arm 62 than is the contact 68 and that the contact 78 is similarly of greater angular length than the contact 77. The reason for this is to insure accurate timing of the instant operation of the switches. In the case 95 of the switch 62, this operation is effected by the inward movement of the front buffers. These buffers move inward taking up the lost motion above-mentioned. As they approach the end of their stroke they move 100 the switch-blade 64 along the contact 67 and just on the completion of their operative stroke the blade 64 passes from the contact 67 to the contact 68.

Similarly in the case of the switch-blade 105 74, when it is operated by the inward movement of the plunger 57. The initial movement of the buffers causes the operative movement of the plunger 57 so that the contact 74 is moved from the contact stud 77 as 110 soon as the buffers begin to move inward. The advantages obtained from this relative dimensioning of the angular length of the contact studs are obtained in all the operations of the switch except when the switch 115 72 is operated from the position shown in Fig. 5 by the outward movement of the plunger 61. The plunger 61 moves outward as soon as the buffers begin to move outward but owing to the length of the contact 78 a 120 very brief interval of time elapses before the blade 74 reaches the contact 77. This however is immaterial in view of the advantages obtained in the other operations.

The various possible positions or setting 125 of the switches are shown diagrammatically in Figs. 6, 7, 8 and 9.

In Fig. 6 the setting is shown when a

coach is independent of any other coach and its buffers are therefore both in their outward position. Both the plungers 57, 61 are "out." The switch 72 is then in its "on" position, but the switch 62 is in its "off" position being drawn thereto by its engagement with the plunger 57.

In Fig. 7 there is shown the setting when the coach is the front coach of a train; that is to say, its front buffers are out and its rear buffers are in. The plunger 57 is pushed in and pushes the switch 72 to its "off" position. The spring 88 being extended rocks the switch 62 into its "on" position, this being permitted by its lost motion connection with the two plungers.

In Fig. 8 the setting is shown when the coach is an intermediate coach of a train that is to say when both the front and rear buffers are in. The plunger 61 pushes both switches 62, 72 into their "off" positions against the action of the spring 88.

Fig. 9 shows the setting when the coach is the rear coach of a train and its front buffers are in but its rear buffers are out. The front plunger 61 still being in its "in" position holds both switches in their "off" position, the rear plunger 57 not affecting either of them.

These four views show all the possible arrangements of the switch-members 62 and 72.

In order to provide for a continuous supply of power for the operation of auxiliary devices on a coach or train where it is being controlled by the sectionalized lines 18 or 19, a third power line 90 may be used as shown in Fig. 3 and in various other figures. It does not, however, affect the method of control of the coach and train as described with reference to Fig. 1. The slipper making contact with this power-line is connected to a terminal 91 in the selector-switch casing, Fig. 5, and this terminal is connected to the studs 69, 79 respectively in order that it may be connected by the operation of the switches to the studs 71, 81 respectively for the purpose hereinafter to be described.

The stud 67 is connected to the slipper 30 on each coach (and thence to the line 12, 18) and the stud 77 is connected to the other slipper 32 on each coach (and thence to the line 19) as illustrated diagrammatically in Fig. 5.

Another element of the control-switch-gear is constituted by an electro-magnetically controlled switch 92 (Fig. 5) which oscillates between two contacts 93, 94. This switch is spring-controlled so that it normally lies against the contact stud 94, but it can be removed therefrom into contact with the stud 93 either by energizing the electro-magnet 95 or by a pin 96 on the plunger 61, the pin being so situated that

when the plunger 61 is in its "in" position 65 the pin holds the contact 92 against the contact 93. A branch-piece 97 on the contact 92 is arranged to make contact at all times with a stud 98. The studs 66, 76 are connected together and a branch taken from them to one end of the winding of the electro-magnet 95. The other end of this winding is connected to a terminal 99 which is connected as hereinafter described to another portion of the apparatus. 75

Other details of equipment of a coach comprise a regulating-device of the type described in the concurrent patent application No. 11979/19 in the name of W. H. Glaser, above noted. This device comprises a mass 80 such as a fly-wheel, means for imparting to it a uniform velocity, acceleration or retardation, and a differential gear whereof one element is driven by this fly-wheel and the other element is driven by the coach, for 85 example, by one of the running wheels of the coach. The differential device is connected to a suitable controlling means, such as a friction clutch or a rheostat in the power circuit of the coach so that the supply 90 of driving power to the coach is varied automatically to maintain its velocity or acceleration or retardation proportional to the predetermined velocity, acceleration or retardation at which the fly-wheel is caused 95 to run. This device is indicated in Figs. 2 and 4 by the reference 67. The precise form of operation of this device will be described later.

Electro-magnetic buffers are also provided 100 at each end of the coach so as to provide for the automatic coupling of two coaches together by suitably energizing the magnets. A reversing switch in the circuit of these magnets provides for uncoupling by reversing the polarity of the magnets in the 105 coach which is to be uncoupled.

A special construction of switch which is suitable for use either as a reversing switch for this electro-magnet circuit or as one of the two-way switches distributed along a track illustrated in Figs. 10, 11 and 12. In this particular embodiment of the switch an annular sheet 101 of brass or other suitable conductor is cut or separated into a 115 series of four contact-pieces 102, 103, 104 and 105 respectively. The intervening pieces all marked 106 are separate from these contact-pieces and merely serve to support the brush on passing from one contact 120 to another. The brushes conveniently take the form of resilient copper strips 107, 108, these two strips being supported on a rotatable arm 109 of insulating material. The brushes are of such length that they bridge 125 from any one of the said contacts to an adjacent one, and by rotation of the switch-member contact is made from any one con-

tact first to the adjacent contact on one side and then to the adjacent contact on the other side, this action taking place repeatedly as the switch-member is rotated through successive right-angles.

Referring to Fig. 10, when the switch is to be used as a reversing-switch the two poles of the circuit are connected to two oppositely disposed contacts 103, 105 and the circuit in which the current is to be reversed is connected between the other two contacts 102, 104. With the brushes 107, 108 in the position shown, the circuit is from the pole 110 through the contact 103, brush 107, contact 102, circuit 111, contact 104, brush 108, contact 105, pole 112. If now the brushes be turned through 90° , say in a clockwise direction, the current in the circuit 111 is reversed, the total circuit being from pole 110 through the parts 103, 108, 104, 111, 102, 107, 105 to the pole 112. Another movement of the brushes of 90° in the same direction will restore the original conditions so that by successively operating the switch in the same direction, the circuit is alternately reversed.

When the switch is to be used as a two-way switch on one pole of a circuit, it is connected as shown in Fig. 11. The main circuit is brought to the contact 103, and the two branch circuits 114, 115, of which one or other is to be connected to the circuit at 103, are connected to the two adjacent contacts 102, 104 respectively. With the switch in the position shown the circuit is made from 103 to 114, and when the switch is turned through 90° a circuit is made from 103 to 105. Rotation of the switch through another 90° returns the circuit to the original form 103 to 114.

It will be seen, therefore, that this switch is particularly adapted for use either as a two-way switch or as a reversing-switch and in both cases it is operated by a continuous step-by-step rotation always in the one direction, that is to say, it may be operated by a striker on the train if the switch is on the track, or by a striker on the track if the switch is on the train.

Fig. 12 shows a construction of two such switches in a single casing and this is conveniently used for example, to combine the switches A^1, B^1 which are both situated at the same point of the track, or the switches a^1, b^1 which are also situated at the same point on the track.

Other parts of the train equipment comprise an electro-magnetic control for the strikers on the train. This is illustrated diagrammatically in Fig. 3 at 116, the striker-pin 117 depending from the casing and being normally held up by a spring but arranged to be drawn down by an electro-magnet so as to be operative on the star-wheel 113 of a switch placed beside the track

or allowed to rise when the magnet has been de-energized so that the pin becomes inoperative. These electromagnets are in circuit with the contacts 71, 81, respectively so that they are energized or de-energized according as the switch blades 65 or 75 are on or off the studs respectively.

As above-described with reference to Fig. 1 separate strikers may be used to operate each series of switches, or as just mentioned a single striker may be used to operate two series of switches arranged in pairs provided the sectionalizing of the various lines is so made that the switches of each set are situated at the same point along the track.

Means are also provided for coupling together automatically certain train-lines which extend throughout the length of each coach so as to provide a continuous line from one end of the train to the other. Any desired form of coupling may be used, it being only necessary that when a coach is coupled to another coach it shall at the same time be electrically coupled thereto in so far as these train lines are concerned.

The operation of the complete electrical equipment of a coach will now be briefly described with relation to Figs. 13, 14 and 15, which show in diagrammatic form the electrical connections on a coach and on a train. Fig. 13 shows the disposition of all the switch gear and connections when the coach is standing in the station or is moving therefrom. Fig. 14 shows a train of three coaches of which the right-hand one is the leading coach. Fig. 15 shows the connections on a coach after it has been slipped from the train and is being retarded on approaching a station.

These diagrams have the same reference letters applied to them as appear on Fig. 5 showing the selector switches, but it will be appreciated that the representation in this case is purely diagrammatic.

Referring first to Fig. 13, the sectionalized coach-control-line 10, the sectionalized part 18 of a train-control-line 12 and the power-line 90 hereinbefore referred to are all shown at the top of the figure. A slipper 118 which makes contact with the power-line 90 is connected to the stud 91 and thence to the two contacts 84, 86, of the auxiliary switches 82, 83 respectively. The other poles 85, 87 of these two switches, are connected together and to a contact strip 119 of a rheostatic device.

The shoe 118 is also connected to the switch member 92, (through the contact 98, see Fig. 5) which oscillates between the two contacts 93, 94. Of these the contact 94 is connected through a coil 120 of high self-induction to the resistance 121 of the rheostat previously mentioned. The other end of this resistance is connected to a train line 122 which extends through the coach and is

automatically coupled up to the other coaches as hereinbefore described when the coaches are coupled together.

The other contact 93 of this pair is connected to one contact of a two-way switch 123, whereof the other poles 124, 125, are connected respectively to an electro-magnetically operated friction-clutch 126, and a brake-device 127, which control the fly-wheel 10 of the regulating device hereinbefore mentioned. The circuit for each is continued to a common line 128 which is earthed at 129, for example, to the running rails of the coach.

15 The slipper 118 on the power-line 90 also supplies a reversing switch designated generally by the reference 130, which controls the electro-magnetic buffers indicated at 131 and 132, these being the front and rear buffers of the coach respectively; they are connected in series or in parallel and are both controlled by the switch 130 so that they are always energized. The switch 130 is a reversing switch, preferably of the type 25 hereinbefore described, and it is mechanically connected with the two-way switch member 123, this mechanical connection being diagrammatically illustrated by a rod 133. Obviously however, the two switches 30 may be combined in a single casing according to the construction shown in Fig. 12.

The selector-switch illustrated in Fig. 5 is shown diagrammatically in Fig. 13. The slippers 30, 32 are connected respectively to 35 the contacts 67, 77 of the switch-members 62, 72. The plungers 57, 61 as illustrated are both in their outward position. The other poles of these two switches 62, 72, are connected together and to the electro-magnet 95 40 (which controls the contact 92). From this electro-magnet the circuit continues to a contact strip 134 which is part of the speed-controlling mechanism hereinbefore mentioned. The circuit, however, is continued 45 from the contact strip 134 through a high resistance 135 and through the common return line 128 to earth at 129. Coöperating with the contact 134 is another contact or series of contacts 136 which are connected to 50 a train-line 137.

The automatic speed control is effected by means of a contact member 138 which is rotated in one direction or the other by the device 67 above-mentioned, according to 55 whether the velocity, acceleration or retardation is greater or less than the pre-determined velocity, acceleration or retardation which is imparted to the fly-wheel. This rotation carries the contact-piece 138 along the 60 contacts 134, 136 in an anti-clockwise direction if the speed is too low, or over contact studs for the resistance 121 and the contact 129 in a clockwise direction if the speed is too high. It will be appreciated that this 65 construction is diagrammatic and reference

is directed to the said co-pending patent application for details of the precise operation and construction of the device.

A constant speed motor is illustrated diagrammatically at 140. In this case it is 70 an electric motor which is connected between the power-line 90 and the earth line; it may obviously be connected between the shoes 118, 129, but for simplicity it is shown as quite separate. This motor runs 75 at a uniform speed and it is controlled by an electromagnetically-operated clutch 141 which couples it to or uncouples it from the driving wheels according as the magnet is energized or not. This electro-magnet is 80 connected between the train line 137 and the common return line 128. Obviously instead of an electric motor 140, any other form of motor, such for example as an internal combustion engine, could be used. 85

An electro-magnetic brake for the coach is indicated diagrammatically at 142 and it is connected between the train line 122 and the common return line 128. 90

When a coach is standing alone in a station, both the buffers are in their "out" position and the two plungers 57, 61, are consequently also out so that the switches 62, 72, occupy the position shown in Fig. 13. The section 19 of the coach control line 95 upon which the slipper 32 is making contact is dead, consequently, there is no current in the circuit 32, 77, magnet 95, contact 134, and resistance 135, similarly also there is no current through the circuit 136 137 100 and clutch 141. Power, however, is being supplied by the line 90 to the constantly running motor 140 and also through the contact 94, rheostat 121 and brake 142, so that the electro-magnetic brake is applied 105 while the coach is standing in the station.

The fly-wheel of the governor device, which is driven through the clutch 126 from any convenient source of power, (for example the motor 140) is disconnected and stationary. 110

When an approaching train energizes the line 19, a circuit is completed from the slipper 32 through the contact 77, electro-magnet 95, contacts 134, 136, train line 137, the 115 clutch 141 and common return line 128. The first operation on completion of this circuit is to move the switch 92 on to the contact 93 and thereby release the brake 142. At the same time the governor-clutch 126 120 is energized and a uniform acceleration is imparted to the fly-wheel. At the same time also the clutch 141 connects the motor 140 to the running wheels of the coach, so that it also starts to accelerate. If the two 125 accelerations are equal the contact piece 138 will remain stationary and the coach will be uniformly accelerated. If on the other hand the coach is accelerating too rapidly, the contact-piece will be carried around in a 130

clockwise direction so that it leaves the contacts 184, 136 and will deenergize the electro-magnetic clutch 141. If this is not sufficient it will move farther and apply the 5 brake 142 by completing the circuit from the shoe 118 through the switch-contacts 84, 85, the contact 119 and resistance 121.

The acceleration and the velocity of the 10 coach are thus caused to follow their predetermined values.

The two-way switch 130 is in such a position that the electro-magnetic buffers 131 and 132 which are both controlled by it are oppositely energized as shown by the letters N S.

When the coach is overtaken by a train, the first operation is that its rear buffers are pushed in and the electro-magnet 132 being energized oppositely to the front magnet of 20 the front coach of the train, the two become locked together. The coach then becomes the front coach of the train as illustrated in Fig. 14. The initial pushing in of its rear buffers causes the plunger 57 to move inward and 25 to rearrange the selector switches 62, 72, in the manner illustrated in Fig. 7, and as also illustrated diagrammatically in Fig. 14 on the right-hand side. The coupling of the coach with the train takes place at the 30 time it leaves the line 19 and it now draws its current by the slipper 30 from the line 12, which is the continuation of the line 18 in Fig. 13. The operation of the switches completes the circuit at the contact 71 and deenergizes the magnet to draw the strikers 31, 34 down so that they become operative. Also the circuit is broken at the contact 81 to deenergize the magnets and allow 35 the strikers 33, 35 to rise to their inoperative position. There is no other rearrangement of the circuits on this car because the two switches 62, 72, are connected together 40 to form the circuit to the magnet 95, consequently the running and control of this 45 coach remain unaltered. The train lines 137, 122, become automatically coupled with the other coaches as shown in Fig. 14.

Simultaneously with the pushing in of the rear buffers of this coach, the front buffers of the front coach of the train overtaking it, are pushed in and at the end of their inward stroke they operate on the selector switches on that coach adjusting them to the setting shown in Fig. 8 and in 55 the middle of Fig. 14.

The new front coach now controls the whole running of the train since the regulating device on it is connected to and supplies the two train lines and through them 60 controls all the magnetic clutches 141 and magnetic brakes 142. As just mentioned in the case of an intermediate coach as shown in the middle portion of Fig. 14 both the front and rear buffers of the coach are in, 65 so that both of the plungers 57, 61, are in,

and the selector switches occupy the position shown in Fig. 8 in which they are both disconnected from their lines 12 (or 18) and 19 and consequently the regulating device is inoperative on every intermediate 70 coach. Similarly on the rear coach where the selector switches occupy the position shown in Fig. 9, both slippers 30 and 32 on the lines 12 and 19 are isolated. Each coach, however, draws power through its 75 slipper 118 from the power-line 90 to energize the clutch 126 for the governor fly-wheel and also for the electro-magnetic buffers. It also draws power if necessary 80 for its main driving motor 140 as above-mentioned, but this motor is operatively connected to the wheels only through its corresponding clutch 141 which is energized through the train line 137 from the front coach. 85

Therefore a whole train is controlled by the governor device of a front coach and whenever a new coach becomes the front coach of a train its governor takes up the control of the train and that of the previous 90 front coach is thrown out of action, as soon as that coach becomes an intermediate coach.

When the last coach of a train is to be slipped to stop at a station, the slipping is 95 effected by a striker on the track operating the reversing switch 130. This is illustrated diagrammatically in Fig. 15 by the rocking of the lever 143. This reverses the polarity of the magnets on that coach so that its 100 front magnets become of similar polarity to the rear magnets of the next coach of the train, and become disengaged therefrom. The operation of this switch also throws over the two-way switch 123. Both 105 mechanical buffers of the coach being now released the selector switches 62, 72, rearrange themselves to occupy the same position as in Fig. 13 and Fig. 6.

Power is now supplied to the coach from 110 the line 19 through the slipper 32, switch 72 and electro-magnet 95 to the regulator device. Power is also still supplied from the line 90 through the slipper 118, switch 92, contact 93 and two-way switch 123 to 115 the braking-device 127 for the fly-wheel of the automatic regulator, thereby imparting a predetermined retardation to the fly-wheel. The control of the coach is now effected by the automatic regulator in the 120 manner hereinbefore described so as to maintain the retardation of the coach equal to or proportional to the predetermined retardation of the fly-wheel. Power is still supplied from the line 90 to the main motor 125 140 in case the coach is being retarded too rapidly and it is necessary to engage the driving motor 140 with the driving wheels.

In the actual operation of slipping the 126 electro-magnetic buffers first release one

another, and their mutual repulsion causes the rear car to separate slightly from the train. At the beginning of each movement the connections of the train lines 137, 122 5 are broken and therefore the power supply to the clutch 141 on that coach is cut off so that no drive is given to the coach and it therefore separates more rapidly from the train. As soon as the coach is clear from 10 the train its forward buffer moves out to rearrange the selector switches, so that power will be supplied from the line 19 through the slipper 32.

When the coach of Fig. 15 enters the 15 station it encounters a striker 144 indicated diagrammatically in Fig. 1 and this striker operates the switches 123 and 130 (or as in the diagram rocks the lever 143) so that they become arranged as in Fig. 13 and a 20 "slipped coach" of Fig. 15 thereby becomes a "coach standing in the station" as illustrated in Fig. 13, and is ready to repeat the full cycle of conditions, *i. e.*, free coach standing at a station, front coach of a 25 train, intermediate coach of a train, rear coach of a train, and coach slipped from a train.

It will be appreciated that in order to insure the satisfactory working of a railway 30 in the manner hereinbefore described, and more particularly in the case of automatic working, it is essential that the time in starting a coach from a station should be determined by the position of the approaching train, and that it should not be varied even by a short interval to suit the desires 35 of passengers.

According to another feature of the invention therefore, turnstiles or some equivalent device are provided at the station to regulate the admission of passengers to the 40 coach standing at the station, and these turnstiles are preferably automatically locked and unlocked according to the position 45 of the approaching train. In Fig. 1 a turnstile is illustrated diagrammatically at 145 and this is electro-magnetically locked and unlocked by a switch or switches situated at a point on the track slightly in advance of the switch a^1 whereof the operation 50 by a train permits the coach to start. When approaching the station therefore the train first of all locks the turnstile 145, then it operates the switch a^1 to cause the coach 55 to start from the station. The turnstile may then be unlocked either by the train operating another switch or the unlocking could be effected by the coach which has been slipped from the train operating a second 60 time the switch which was operated by the train to effect the locking of the turnstile. Another convenient arrangement is one in which two two-way switches are used, one being operated by the operative striker on

the front coach of a train, the other switch 65 being operated by the striker at the rear end of the coach which striker is operative after the coach has been slipped.

It will be appreciated that the control of the power supply of braking of a coach and 70 train may be effected in various ways other than that above-described. Thus, for example, the control circuits may be used to operate electro-magnetic relays which in their turn operate devices to apply either 75 driving power or braking power to the running wheels of the vehicles. Thus, for example, it lies within the scope of this invention to control a train automatically in the manner above-described when the driving power is supplied to a train by say an internal-combustion engine and the braking-power by means of ordinary compressed air brakes.

It also lies within the scope of this invention to eliminate a certain amount of the automatic control. Thus, for example, a driver on the train might control the starting and stopping of the fly-wheel of the automatic regulator and thereby control the 90 speed of the train. Alternatively, it could have direct control of the train in so far as the train equipment is concerned, while retaining the sectionalized lines which determine the relative positions of a coach and 95 a train.

It also lies within the scope of this invention to provide for a mutual control between two trains on the line in the same way as control is provided between a coach 100 and a train. In this case the line 12 would be sectionalized throughout its length and the switches to control the section for a complete train would themselves be controlled by another train, preferably the train in advance of it.

What we claim as our invention and desire to secure by Letters Patent is:—

1. In a railway-system, the combination of a track, stations disposed along it, an aggregation of vehicles constituting a train adapted to travel along the track past a station, means for establishing communication for passengers between the vehicles of said train, a vehicle adapted to stand on the 110 track at said station to receive passengers in it, means directing said vehicle to leave the station in advance of the said train when said train approaches within a pre-determined distance of said station and means 115 permitting the said train to overtake said vehicle at a pre-determined distance from said station.

2. In a railway-system, the combination of a track, a vehicle accelerating therealong, 125 a second vehicle traveling on the same track behind the first vehicle, means operated by one vehicle to govern the movement of the

other vehicle in such manner that the space between them is determined by the distance they have traveled along the track.

3. In a railway-system, the combination 5 of a track, a vehicle traveling thereon at an accelerating speed, a second vehicle traveling at a uniform speed on the same track behind the first vehicle, means operated by the first vehicle to control the movement of 10 the second vehicle and limit its approach to the first vehicle until the first vehicle has attained a speed approximately equal to that of the second vehicle.

4. In a railway-system the combination 15 of a track, a vehicle traveling thereon at an accelerating speed, a second vehicle traveling at a uniform speed greater than the speed of the first vehicle upon the same track and behind it, means operated by the first 20 vehicle to control the movement of the second vehicle in such manner that it can overtake the said first vehicle only when the speed of the first vehicle is approximately equal to that of the second vehicle, means 25 operated by the second vehicle to prevent the first vehicle attaining a speed greater than that of the second vehicle and to insure that the first vehicle shall be overtaken by the second vehicle.

30 5. In a railway-system the combination of a track arranged as a closed ring, stations disposed along the track, an aggregation of vehicles constituting a train which does not stop at a station, means for slipping the last vehicle from the train to provide transport to each station, a vehicle allocated to each station to provide transport therefrom, and means directing said vehicle to start from the station when the train is within a 35 pre-determined distance from the station and to accelerate therefrom in advance of the train till it attains such a speed that it can be coupled to the train.

6. In a railway-system the combination of 45 a track arranged as a closed ring, stations disposed along the track, an aggregation of vehicles constituting a train which does not stop at a station, means for slipping the last vehicle from the train to provide transport to each station, a vehicle allocated to each station to provide transport therefrom, means directing said vehicle to start from the station when the train is within a pre-determined distance from the station and to 50 accelerate therefrom in advance of the train till it attains such a speed that it can be coupled to the train, means operated by the train to control the movement of the vehicle, means operated by the vehicle to control the movement of the train in such manner that the space between them is determined by the distance they have traveled along the track, means for coupling said vehicle to the front of the train when overtaken by the train, and means establishing

communication between the vehicles when coupled together in a train.

7. In an electric railway-system the combination of a track, a coach traveling thereon at an accelerating speed, a train traveling 70 behind the coach to overtake it, a control-line for the train divided into insulated sections, a series of switches adapted to be operated by the coach spaced along the track from the starting point of the coach and each controlling one of said insulated sections, the spacing of said switches being pre-determined from the acceleration characteristic of the coach and the velocity of 80 the train so that the coach shall have attained a pre-determined velocity and position before it energizes each of said sections of said train-control-line, whereby the decrease of the space-interval between the 85 train and the coach is governed by the velocity and position of the coach.

8. In an electric-railway-system, the combination of a track, stations disposed therealong, a train thereon, a train-control-line divided into insulated sections in the neighborhood of each station thereon, the sectioned part of the line extending in both directions along the track from the station, a series of switches spaced along the track 90 in one direction from the station, said switches each controlling the power-supply to one of said insulated sections, a coach adapted to operate said switches when it leaves the station, a coach-control-line divided into insulated sections and extending from the station in the direction in which the coach leaves the station, a second series of switches spaced along the track and adapted to be operated by the train to control the power-supply to each of the sections 95 of the coach-control-line, the spacing of the switches of the said first and second series being pre-determined from the acceleration 100

characteristic of the coach and the velocity 110 of the train so that the energizing of each section of the coach-control-line to permit the coach to travel therealong shall occur only when the train has reached a pre-determined distance from that section, and that 115 the energizing of the sections of the train-control-line to permit the passage of the train therealong shall take place only when the coach is a pre-determined distance in advance of said section, and that the train 120 shall be permitted to overtake the coach when the coach has attained a speed approximately equal to that of the train.

9. In an electric railway-system, the combination of a track, a train-control-line divided into insulated sections, a coach-control-line divided into insulated sections, a two-way switch connected to each section at the end by which a vehicle leaves that section in its normal direction of travel, one 125

series of two-way switches each interconnected with a two-way switch controlling a section of the train-control-line, said switches being spaced along the track at 5 points remote from the sections of the train-control-line which they control and in the direction in which vehicles travel along the track, a second series of two-way switches each interconnected with one of the two-way switches controlling the sections of the 10 coach-control-line, each of said second series of switches being spaced along the track away from the section which it controls in the direction from which vehicles approach 15 the said section.

10. In an electric railway-system, the combination of a track, coaches on the track, a sectionalized control-line, a pair of two-way switches interconnected with one another 20 and with each section of said control-line to control it, said switches being spaced along the track, strikers on each coach to operate said switches by the passage of the coach, and means selectively rendering operative 25 said strikers.

11. In an electric railway-system the combination of a track, coaches thereon, a train-control-line divided into insulated sections, a coach-control-line divided into insulated 30 sections, a two-way switch connected to each insulated section at the end by which a vehicle leaves that section in its normal direction of travel, a series of two-way switches each interconnected with a two-way switch 35 controlling a section of the train-control-line, said series of switches being spaced along the track away from the insulated sections to which they are connected, a second series of two-way switches each interconnected 40 with a two-way switch controlling a section of the coach-control-line and spaced away along the track from the section to which it is connected, a striker on each coach adapted to operate the two-way switch at the end of 45 the section when the coach leaves that section, a striker on each coach adapted to operate each of the first series of switches controlling the section of the train-control-line, and another striker on each coach adapted 50 to operate each of the switches of the second series of switches controlling the sections of the coach-control-line, and means for selectively rendering said strikers operative.

12. In an electric railway-system, the combination of a track, a train thereon, a coach thereon, a sectionalized train-control-line, a sectionalized coach-control-line, switches controlling said sections and spaced along the track, strikers on each 60 coach for operating said switches, automatic means selectively rendering said strikers operative according as a coach is coupled to a train, or is free therefrom.

13. In an electric railway-system, the combination of a track, a train thereon, a coach

thereon, a sectionalized train-control-line, a sectionalized coach-control line, pairs of two-way switches interconnected with one another controlling each section of each of the control-lines and spaced along the track, 70 strikers on each coach for operating said switches, means connecting the buffers on each coach to said strikers to render said strikers operative or inoperative according as the buffers are pressed in by the engagement of a coach with another coach or are extended when the coach is free. 75

14. In an electric railway-system, the combination of a track, a train thereon, a coach thereon, a sectionalized train-control-line, a sectionalized coach-control-line, switches interconnected with said sections and spaced along the track, electro-magnetically controlled strikers on each coach for operating said switches, electric switches on each coach 80 interconnected with the buffers on that coach so as to be moved thereby to control the circuits of the electro-magnets for the strikers, and render them selectively operative or inoperative according as the buffers of a coach 85 are free or are engaged by the buffers of another coach. 90

15. In an electric railway-system, the combination of a track, a train-control-line and a coach-control-line, each extending along 95 the track, coaches on the track, power-driving means on each coach, slippers on each coach making contact respectively with the train-control-line and coach-control-line, and switches adapted to connect either slipper to 100 a controlling circuit for the said driving means.

16. In an electric railway-system, the combination of a track, stations disposed therealong, a train-control-line extending along 105 the track and sectionalized in the neighborhood of each station, a coach-control-line sectionalized on that portion of it extending from a station in the direction of traffic from that station, coaches on said track, 110 power-driving means on each coach, two slippers on each coach making contact respectively with the coach-control-line and train-control-line, and switches adapted to connect either slipper to the controlling circuit for the said driving means, said switches being automatically operated to select one or other slipper according as a coach is coupled to the other coaches in a train or is 115 free.

17. In an electric railway-system, the combination of a track, stations disposed therealong, a train-control-line and a coach-control-line extending along the track and sectionalized in the neighborhood of each station, coaches on said track, power-driving means on each coach, two slippers on each coach making contact respectively with the coach-control and train-control-line, switches adapted to connect either slipper to the con- 125 130

trolling circuit for the said driving means and operative connections between said switches and the buffers on the coach to operate them according as the buffers of the 5 coach are engaged by the buffers of another coach or are free.

18. In an electric railway-system, the combination of a track, stations disposed therealong, a train-control-line extending along 10 the track and divided into insulated sections in the neighborhood of each station, a coach-control-line divided into insulated sections on a portion of it extending from a station in the direction of traffic from that 15 station, coaches on said track, track-switches spaced along the track and automatically operated by said coaches to control the said insulated sections of the train-control-line and coach-control-line respectively, power-driving 20 means on each coach, two slippers on each coach, making contact respectively with the train-control-line and coach-control-line, movable buffers at the front and rear ends of each coach adapted to be engaged by 25 the buffers of other coaches, switch-members operatively connected to said buffers to be moved thereby, contacts coöperating with said switches and selectively connecting either of said slippers to a controlling 30 circuit for said driving means, strikers on each coach adapted to selectively operate said track-switches, electro-magnets adapted to render said strikers operative, and additional contacts coöperating with said buffer-operated switches to control said electro-magnets.

19. In a railway-system, the combination of a track, a vehicle accelerating therealong, a second vehicle traveling on the same track 40 behind the first vehicle, power-driving means on each vehicle, a controlling circuit for said driving means, a governor-device in said controlling circuit operative to cause the vehicle to travel at a pre-determined speed, 45 acceleration, or retardation, and means operated by each vehicle to govern the movement of the other vehicle in such manner that the space between them is determined by the distance they have traveled along the 50 track.

20. In a railway system, the combination

of a track, stations disposed therealong, an aggregation of vehicles constituting a train adapted to travel along the track past a station, means for establishing communication 55 for passengers between the vehicles of said train, a vehicle adapted to stand on the track at the said station to receive passengers in it, a gate controlling the admission of passengers to said coach, locking means for said 60 gate operated by said train when it approaches within a pre-determined distance of said station, means directing said vehicle to leave the station in advance of the said train when the train approaches within a 65 pre-determined distance of said station, and means permitting the said train to overtake the said vehicle at a pre-determined distance from said station.

21. In an electric railway-system, the combination of a track, coaches thereon, a train-control-line extending therealong and divided into insulated section, a coach-control-line extending therealong and divided into insulated sections, pairs of two-way switches 70 interconnected with and controlling each of said insulated sections, strikers on said coaches adapted to operate said switches, said switches each comprising a rotatable spindle, four contact-pieces arranged in a 75 circle around said spindle, insulating conducting bridges carried on said spindle adapted to connect any one of said contacts to an adjacent contact and means on said spindle adapted to be engaged by said 80 strikers of said coaches.

22. In a railway-system, the combination of a track, stations disposed therealong, an aggregation of vehicles constituting a train which does not stop at a station, electro-magnetic means coupling said vehicles together in said train, a reversing switch on 90 each of said vehicles controlling said electro-magnetic coupling means, a striker on said track adapted to engage and operate said 95 reversing switch to release said coupling and slip a vehicle from the train.

In testimony whereof we have signed our names to this specification.

GEORGE BERTHOLD SAMUELSON.

WILLIAM HENRY GLASER.
